UNITED STATES PATENT OFFICE.

ADOLPH C. RECKER, OF OAKVILLE, CONNECTICUT, ASSIGNOR TO WATERBURY MFG.
CO., OF WATERBURY, CONNECTICUT, A CORPORATION.

MINER'S LAMP.

1,283,897.

Specification of Letters Patent.

Patented Nov. 5, 1918.

Application filed January 19, 1918. Serial No. 212,541.

To all whom it may concern:

Be it known that I, ADOLPH C. RECKER, a citizen of the United States, residing at Oakville, in the county of Litchfield and State of Connecticut, have invented a new and useful Improvement in Miners' Lamps, and I do hereby declare the following, when taken in connection with the accompanying drawings and the characters of reference 10 marked thereon, to be a full, clear, and exact description of the same, and which said drawings constitute part of this application, and represent, in—

Figure 1 a view partly in side elevation, and partly in vertical section, of an acetylene gas miner's lamp embodying my invention.

Fig. 2 a detached broken view of the carbide-receptacle thereof, showing the closure for its spare-part chamber removed.

Fig. 3 a detached view in side elevation of the said closure.

My invention relates to an improvement in that class of miner's lamps which burn acetylene gas produced by slowly feeding 25 water under valve-control to calcium carbide, the object being to produce a lamp of the character described, provided with a double or shock-proof bottom and a simple, convenient, unobtrusive spare-part chamber 30 for the storage of such spare parts as the miner may need for replacements, without appreciably increasing the weight of the lamp.

In carrying out my invention, I employ a part-part cap or closure 2 having an up-standing threaded flange 3 adapting it to be sleeved over and screwed upon a band of threads 4 formed upon the lower end of a carbide-receptacle 5 the bottom of which is 40 struck inward and upward to form a concentric dome-like deflector 6 which stiffens the receptacle and forms within the bottom thereof a circular spare-part chamber 7 which is closed by the closure or cap 2 aforesaid. The said chamber as thus produced, is sufficiently capacious to receive spare burner-tips 8, washers, and such other small parts of the lamp as it may be necessary from time to time to replace, and which it is

a matter of great convenience for a miner 50 to have with him. The inwardly struck bottom 6 aforesaid and the bottom of the cap or closure 2, together form a double or shock-proof bottom for the lamp, this feature being found efficacious in preventing 55 the lamp from being extinguished by the shocks due to blasting or other explosions in the mine. The deflector 6 is centered with respect to the lower end of the water-tube 9 and operates to uniformly deflect into the 60 bottom of the carbide-receptacle 5, any water which is not immediately taken up by the carbide on its entrance into the receptacle. This uniform distribution of the water makes the generation of the gas, and hence 65 the operation of the lamp, more uniform. Otherwise than described, the lamp may be of any approved construction. As herein shown the carbide-receptacle 5 is surmounted by a water-reservoir 10 above which shows 70 the finger-piece 11 by means of which the flow of water is controlled. The lamp is also provided with the usual reflector 12 and sparking-device 13.

I claim:—

75
In a miner's lamp, the combination with a carbide-receptacle having its bottom struck inwardly to form a concentric internal space and a centralized domical water-deflector, and the lower portion of the said receptacle 80 being formed with peripheral screw threads, of a water-receptacle superimposed upon the carbide-receptacle, a water-tube extending downward from the water-receptacle into the carbide-receptacle and having its lower 85 end centered above the said deflector; and a spare part cap applied over the threaded bottom of the carbide-receptacle and uniting with the said space to form a spare part storage chamber and also forming a double 90 or shock proof bottom for the lamp.

In testimony whereof, I have signed this specification in the presence of two subscribing witnesses.

ADOLPH C. RECKER.
